4 Claims. (Cl. 307—12)

1

This invention relates generally to improvements in power supplies of the full wave rectification type.

A primary object of the invention resides in the provision of a full wave rectifier supply for delivering direct current potentials to a plurality of vacuum tubes some of which are to be operated at certain times, and all of which are to be operated at other times.

More specifically, the invention is particularly applicable for use in combined television and high-frequency radio chassis wherein all of the vacuum tubes are used during television reception and only a portion of vacuum tubes are used during radio reception.

A still further object is to provide a double rectifier type of supply including switch means for disabling operation of one of the rectifiers during radio reception and connecting both of the rectifiers in a manner for cooperative operation during television use when all of the vacuum tubes are employed.

A further object is to provide a power supply of the above type wherein the disabling of direct current potentials to a portion of the tubes does not result in a rise in the potential delivered to the other tubes in the circuit.

Another object is to provide a power supply which is adapted for use with a main line A. C. voltage which may vary widely as to average potential.

Further objects and advantages of the invention will become apparent to persons skilled in the art upon an examination of the drawing, the description and the claims appended thereto.

The single drawing illustrates schematically a circuit arrangement of power supply in which the present invention has been incorporated.

Referring to the drawing, a main transformer 2 includes the usual primary winding 3, a core 4, a high voltage center tapped secondary winding 5 and a low voltage cathode heater winding 6. The primary winding 3 is provided with a plurality of taps 7, one of which 8 is connected by lead 9 to the primary 10 of a second transformer, generically designated 11, the opposite end of primary 10 being connected through lead 12 and switch 13 back to the end of winding 3 and to one side of an A. C. power main terminal 15, the opposite main terminal 16 being connect-

2

ed to the other end of primary 3 as shown. This tapped arrangement permits use of the power supply on mains supplying potentials varying from 110 to 240 volts.

Transformer 11 includes core 19, a pair of center tapped high voltage secondary windings 20 and 21 and a low voltage cathode heater winding 23. Secondary winding 5 of transformer 2 is divided by center tap 25 into two equal coil portions 26 and 27, and center tapped secondaries 20 and 21 of transformer 11 are divided by their center taps 30 and 31 into equal coil portions 32, 33 and 34, 35, respectively. The outer end of coil portion 26 is series connected by lead 37 through coils 32, 33 and lead 38 to anode 39 of a full wave rectifier tube 40. The end of coil 27 is connected by lead 42 and through coil portions 34, 35 and lead 43 to the opposite anode 44 of rectifier 40. Center taps 30 and 31 of coils 20 and 21 are connected respectively through leads 46 and 47 to anodes 48 and 50 of full wave rectifier tube 52. The cathode heater coils 6 and 23 are connected in a conventional manner as shown to the cathodes 53 and 54 of rectifier tubes 52 and 40 respectively to complete the circuit.

The operation of the device is as follows. Lead 60 serves as a common negative or ground lead from center tap 25 to the cathode of ground portions of a circuit to be supplied with direct current voltages, as for example, the radio portion of a combined television and radio receiver. The cathodes of the various tubes therein may be supplied with alternating heater current from transformer 2. Lead 61, taken from the cathode circuit of rectifier tube 52, serves as the positive lead to a filter and then to the elements of the various vacuum tubes requiring direct current potentials, the usual dropping resistors being employed to provide the selective potentials required, none of this conventional circuitry being shown.

Assuming in the circuit shown that the output of rectifier 52 is utilized to supply the required direct current operation potentials to the radio portion of a combined television and radio receiver, and that the output of rectifier 40 is utilized to supply operating potentials to those vacuum tubes which are incorporated in the television, but not in the radio circuit, the operation of rec-

ifier tube 40 is independent of and unaffected by concurrent operation of rectifier tube 52. Secondary coils 20 and 21 of transformer 11 serve as a single center tapped secondary with the inner ends thereof maintained at zero potential at the center tap 25 of the secondary coil 5 of transformer 2. It is apparent that since the respective inner ends of coils 20 and 21 are connected by leads 37 and 42 to the respective outer ends of coil 5, voltage induced in coil 5 from primary 3, being equal and opposite in the coil portions 26 and 27, does not alter the zero potential at the inner ends of coils 20 and 21 thus joined, hence lead 60, connected to center tap 25 serves as a common negative or ground lead for both rectifier tubes 40 and 52. The outer ends of coils 20 and 21 are connected to anodes 39 and 44 of rectifier 40 through leads 38 and 43, thus rectifier 40 serves as a conventional full wave rectifier to deliver a positive output between leads 70 and 60.

Operation of rectifier 52 as described above is modified to some extent with switch 13 closed and transformer 11 operative. Whereas with transformer 11 inoperative, coil portions 32 and 35 of secondaries 20 and 21 did not appreciably change the output of rectifier 52, with the transformer 11 operative, coil portions 32 and 35 are serially added to coil portions 26 and 27 respectively of secondary 5, transformer 2, to produce a higher alternating current potential at anodes 48 and 50 respectively of rectifier 52. The circuit connections between the transformers are such that the induced voltages in coil portions 32 and 35 of transformer 11 add to rather than oppose the induced voltages in coil portions 26 and 27 of transformer 2 respectively.

It is thus seen that for a given load, the rectified output potential appearing between conduit 61 and 60 is somewhat greater when transformer 11 is connected in circuit. As mentioned above, the output of rectifier 40 may be utilized to supply direct current potentials to those tubes employed for television reception only, but a preferred use of the above circuit is as follows. The output of rectifier 40 may be employed to supply only the very high operation potentials required by one or more of the television circuit tubes, whereas the output of rectifier 52 may be employed to supply operating potentials to all of the radio circuit tubes plus some of the television circuit tubes. In this instance, cathode current for the radio circuit tubes is drawn from transformer 2 whereas the cathode current for all of the television circuit tubes are drawn from transformer 11. With transformer 11 inoperative, the rectified output between leads 61 and 60 is at an optimum value for the radio circuit tubes, and while certain of the television circuit tubes are connected to the same output, those tubes draw no current since no cathode heater current is supplied thereto. Upon closing switch 13, heater current is supplied to the television circuit tubes, throwing a greater load on rectifier 52, which would normally result in a drop of the output potential between leads 60 and 61. Because as above explained, the output of rectifier 52 is higher with transformer 11 operating, the normally higher output therefrom is reduced by the additional load to substantially the value maintained on the radio circuit tube elements with transformer 11 inoperative.

It is thus seen that the circuit not only results in economies due to a saving in power

consumption, but provides substantially constant operating potentials for either a relatively few tubes or a relatively large number of tubes, a result which could otherwise only be obtained by providing a somewhat heavier power supply shunted with a relatively heavy dropping resistance for maintenance of fairly constant operating potentials irrespective of a major change in load. The circuit is therefore productive of the additional advantage of substantially reduced construction costs since smaller transformers and rectifiers may be utilized than would otherwise be required.

While I have described above the principles of my invention in connection with specific apparatus it is to be clearly understood that this description is made only by way of example and not as a limitation to the scope of my invention as set forth in the objects thereof and in the accompanying claims.

What is claimed is:

1. In a circuit for supplying a plurality of electron discharge devices with cathode and anode voltages, a main transformer including a primary, a center tapped high voltage secondary and a low voltage secondary, a second transformer including a primary, a pair of center tapped secondaries and a low voltage secondary, means switch connecting the primary of said second transformer to the primary of said main transformer, first and second full wave rectifiers each including two anodes and a cathode, circuit means connecting the center taps of the secondaries of said second transformer to the anodes respectively of said first rectifier, with the outermost windings thereof connected to the respective anodes of said second rectifier, and the innermost windings thereof connected to the outermost windings of the center tapped secondary of said main transformer, and means connecting the low voltage secondary windings of said main and second transformers to the cathodes of said first and second rectifiers whereby direct current operating potentials for some of said devices may be obtained between the center tap of the high voltage secondary of said main transformer and the cathode of said first rectifier, and direct current potentials for other of said devices may be obtained between the said center tap and the cathode of said second rectifier.

2. In a device of the character described, a first transformer including a primary, a high voltage center tapped secondary and a low voltage secondary, a second transformer including a primary, a pair of high voltage center tapped secondaries, and a low voltage secondary, first and second full wave rectifiers, means series connecting each of the high voltage secondaries of said second transformer between the respective ends of the high voltage secondary of said first transformer and the anodes, respectively, of said second rectifier, means connecting the low voltage secondary windings of said first and second transformers to the cathodes of said first and second rectifiers respectively, and means connecting the center taps of the high voltage secondary winding of said second transformer to the anodes of said first rectifier, whereby, in the absence of excitation current applied to the second transformer, said first rectifier is connected to the high voltage secondary of said first transformer through portions of the tapped secondaries of the second transformer to deliver full wave rectified output between the center tap of the high voltage secondary winding of said first

transformer and the cathode of said first rectifier, and with the second transformer energized, said first rectifier delivers an output of higher potential from the same points in the circuit, with said second rectifier delivering an independent direct current between the same center tap and the cathode thereof.

3. The circuit of claim 2 wherein the primary of said first transformer is provided with taps at one end thereof, the primary of said second 10

transformer being connected to one of said taps and to the untapped end thereof.

4. The circuit of claim 1 wherein the primaries of said first and second transformers are interconnected to provide selective impedance to a source of energizing current.
